UNITED STATES PATENT OFFICE

1,999,070

TOILET SEAT LIFTER

Lorentz D. Svedelius, Melbourne, Fla.

Application April 24, 1934, Serial No. 722,195

1 Claim. (Cl. 4—251)

The invention relates to a toilet seat lifter and more especially to a foot controlled toilet seat lifter.

The primary object of the invention is the provision of a device of this character, wherein a toilet seat, by manipulation of the foot of a person, can be conveniently lifted and when the foot has been released the seat will be lowered onto the bowl, the device being of novel construction and convenient and handy for use.

Another object of the invention is the provision of a device of this character which is extremely simple in construction, thoroughly reliable and efficient in its purpose, readily and easily applied to and removed from a toilet fixture, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claim hereunto appended.

25 In the accompanying drawing:

Figure 1 is a side elevation of a toilet bowl showing a seat and cover, with the device constructed in accordance with the invention applied to the seat, the latter being shown by full lines in lowered position and by dotted lines in raised position.

Figure 2 is a front elevation.

Figure 3 is a perspective view of the device detached.

30 Similar reference characters indicate corresponding parts throughout the several views in the drawing.

Referring to the drawing in detail, A designates generally a toilet bowl of conventional or

standard type and B the seat which is suitably hinged so that it can be raised and lowered from and onto the bowl, as is common.

The device comprises a bracket 5, preferably made from a flat bar bent to provide an attaching end portion 6 having the bight 7 therein to conform to the flanged base 8 of the bowl A, and this end 6 is made fast to an anchoring bolt 9 for the bowl. The other end of the bracket 5 constitutes an upright or supporting post 10 for a vertically swinging lever 11 which is pivoted to the upright or post, as at 12, while at the outer end of the lever is a foot-engaging head 13, and loosely connected to the inner end of the lever is a link 14, the latter at its uppermost end being journaled in a bearing 15 secured to the bottom face of the seat B.

The parts of the device are located at one side of the bowl A and by foot pressure upon the head 13 the seat B can be raised from the bowl to an elevated position, as is clearly shown by dotted lines in Figure 1 of the drawing, the normal position of the seat being lowered, as shown by full lines in Figures 1 and 2 of the drawing.

25 What is claimed is:

The combination of a pair of levers, one lever having right-angular ends, the other lever having a hole in one end for loosely receiving one right-angular end of the other lever, a bearing 30 for mounting upon a cover of a toilet bowl and loosely receiving the other right-angular end of said other lever, a foot-engaging portion on the lever having the hole and at the other end thereof, and a bracket for engaging a base fastener of said bowl and having the lever carrying the foot-engaging portion pivotally supported thereby.

35 LORENTZ D. SVEDELIUS.
